UNITED STATES PATENT OFFICE.

ROBERT B. DONALDSON AND EMMETT QUINN, OF WASHINGTON, D. C.

IMPROVEMENT IN STEAM-GAGES.

Specification forming part of Letters Patent No. 66,311, dated July 2, 1867.

To all whom it may concern:

Be it known that we, ROBERT B. DONALDSON and EMMETT QUINN, of Washington city, in the District of Columbia, have invented a new and useful Improvement in the Manufacture of Compound Siphon Steam-Gages, invented by Emmett Quinn, and patented by him March 13, 1866, and March 12, 1867; and we do hereby declare the following is a full, clear, and exact description of the construction and operation of the same, reference being had to the accompanying drawings, in which—

Figure 1 is a front view. Fig. 2 is a vertical section.

Like letters in the figures of the drawings indicate like parts.

The nature of our invention and improvement consists in the application and use of india-rubber, gutta-percha, or their compounds, or any other suitable material, in the manufacture of steam-gages.

To enable others skilled in the art to make and use our invention, we will proceed to describe its construction and operation.

Letter A is a tubular column, composed of india-rubber, gutta-percha, or their compounds, or other suitable material, of proper size, and molded or carved in a neat shape and style. B B are tubular pipes, of proper diameters, extending through the entire length of the column A, and answer the place and purpose of the metallic siphons or tubes heretofore used in such steam-gages. These tubular pipes may be molded with and in the column A around metallic cores, which may consist either of thin tubes supported on mandrels, or around smooth, straight metallic rods, prepared and arranged for that purpose, at proper distances apart, and parallel, so that the partitions between and the outside walls of the tubular pipes will be of sufficient thickness to afford the required strength, the mandrels or rods to be withdrawn when the molding is complete; or the column A may be molded solid, and the holes may be drilled. (See Figs. 3 and 4, which represent the hollow cores with the mandrels withdrawn, Fig. 2 representing the tubes with the solid cores or rods withdrawn.)

Communication between each of the tubular pipes is effected by the grooves h h at alternate ends, substantially the same as in the patent referred to.

The ends of the tubular holes are securely closed by proper packing under the metallic caps C C, tightly fastened on the ends of column A by means of the screws D D and the metallic nuts E E, so as to entirely prevent the escaping of the fluids.

To guard against and prevent any injurious effects of heated steam coming directly in contact with the rubber or gutta-percha, a metallic tube, H, of proper size and length, and properly constructed to connect with the steam-pipe, is placed or molded into the first tubular pipe, and receives the direct pressure and effects of the steam, communicating the pressure to the other tubular holes through the grooves h h.

A suitable scale, F, and glass tube G, with an elastic reservoir, for the purpose of adjusting the level of the mercury to the zero-point in the index-tube, as shown in the patent referred to, are arranged upon and in the front of the gage, so as to indicate the exact pressure of the steam. A supplementary elastic reservoir may also be applied to the central tube of the gage, to more effectually accomplish what is now, in a great measure, done by the one attached to the index-tube, as shown in the patent above referred to.

The rubber gage thus constructed can be manufactured with much greater facility, in a neater style, at much less expense, and will be much lighter than the metallic steam-gages.

Having thus fully described our invention, what we claim therein as new, and desire to secure by Letters Patent, is—

1. The construction of tubes for steam-gages of india-rubber, gutta-percha, or their compounds, or other suitable material, substantially in the manner and for the purposes as herein set forth.

2. The construction of hollow cores of metal, or other suitable material, supported by mandrels, substantially in the manner and for the purposes as herein set forth.

R. B. DONALDSON.
EMMETT QUINN.
